UNITED STATES PATENT OFFICE.

MAHLON M. CARR, OF FOSTORIA, OHIO.

RAILWAY-TORPEDO.

SPECIFICATION forming part of Letters Patent No. 688,930, dated December 17, 1901.

Application filed June 17, 1901. Serial No. 64,887. (No model.)

To all whom it may concern:

Be it known that I, MAHLON M. CARR, a citizen of the United States, residing at Fostoria, in the county of Seneca and State of Ohio, 5 have invented a new and useful Railway-Torpedo, of which the following is a specification.

This invention relates to railway-torpedoes, and has for its objects to provide improved means for securing the rail-embracing 10 strip to the torpedo so as to obviate displacement thereof from the torpedo and also to arrange for facilitating the assemblage of the parts of the device.

With these and other objects in view the 15 present invention consists in the combination and arrangement of parts, as will be herein-after more fully described, shown in the accompanying drawings, and particularly pointed out in the appended claim, it being understood that changes in the form, proportion, size, and minor details may be made 20 within the scope of the claim without departing from the spirit or sacrificing any of the advantages of the invention.

25 In the drawings, Figure 1 is a perspective view showing the present form of torpedo applied to a rail. Fig. 2 is a central sectional view of a torpedo constructed in accordance with the present invention. Fig. 3 is a perspective view of the bottom member of the 30 torpedo. Fig. 4 is a detail perspective view of the top member. Fig. 5 is a detail top plan view with the cap member removed.

Like characters of reference designate corresponding parts in all of the figures of the 35 drawings.

Referring to the drawings, 1 designates the bottom member of the torpedo, which is in the form of a cylindrical box, having an open 40 top and an outwardly-directed marginal flange or rim 2, surrounding the open edge and provided with diametrically opposite notches or recesses 3. Within this bottom member there is fitted a cylindrical box-like 45 member 4, which fits snugly the bottom member and has a diametric groove or seat 5 pressed in the upper side thereof. This top member is first inverted and filled with suitable detonating material 6, after which the 50 bottom member is applied to the top member, and the telescoped members finally inverted to their normal position. The pliable metallic fastening-strip 7 is then placed in the seat 5 with its opposite end portions bent down- 55 wardly into the respective notches in the rim

or flange 2 of the bottom member, the two members having been previously adjusted to register the notches with the respective ends of the seat or groove. Finally a cylindrical box-like cap member 8 is fitted snugly downwardly upon the top member, so as to embrace the portions of the fastening-strip which lie across opposite edges of the device, and thereby hold the same in the notches of the bottom member. 60

In applying the torpedo to a rail, as shown in Fig. 1, it is placed upon the top of the tread thereof and the free projected ends of the fastening-strip bent snugly around the opposite side edges and underneath portion of the tread, thereby holding the torpedo to the rail in position to be crushed by the wheels of a train and to give out a loud report as a signal. 65

From the foregoing description it is apparent that the parts of the present invention 70 may be conveniently assembled and are each designed to be formed from a single blank of sheet metal, which is pressed into the form of a cylindrical box of the required size, whereby the device is inexpensive; also, the fastening-strip embraces the telescoped top and bottom members, thereby bracing and stiffening the same and increasing the detonating 75 effect of the torpedo.

What is claimed is—

A railway-torpedo, comprising telescoped 80 top and bottom box-like members, of which the upper member fits snugly within the bottom member, and is provided with a groove or seat formed across the top thereof, the bottom member having an upper outwardly-directed marginal rim or flange provided with opposite notches registered with the respective ends of the groove or seat of the top member, a pliable fastening-strip having its intermediate portion seated in the groove or seat and bent downwardly through the respective notches, the end portions of the strip being free for engagement with a rail, and a cap member 85 snugly embracing the top member and the portions of the fastening-strip which are bent into the notches of the bottom member. 90

In testimony that I claim the foregoing as my own I have hereto affixed my signature in the presence of two witnesses.

MAHLON M. CARR.
